CLAIM

The ornamental design for a scissors for holding interchangeable blades, as shown and described.

DESCRIPTION

FIG. 1 is a side elevational view showing our new design for a scissors for holding interchangeable blades with the opposite side being a mirror image;

FIG. 2 is a top plan view thereof;

FIG. 3 is a front elevational view thereof; and

FIG. 4 is an enlarged cross-sectional view of the holder illustrating the blade in broken lines.
